Inventor

E. Thayer

United States Patent Office.

ELI THAYER, OF WORCESTER, MASSACHUSETTS, ASSIGNOR TO HIMSELF
AND MARSHALL COWING, OF NEW YORK CITY.

Letters Patent No. 97,001, dated November 16, 1869.

IMPROVED MODE OF COLLECTING AND STORING CARBONIC ACID FOR EXTINGUISHING FIRES.

The Schedule referred to in these Letters Patent and making part of the same.

To all whom it may concern:

Be it known that I, ELI THAYER, of the city and county of Worcester, in the State of Massachusetts, have invented a new and useful Method of Utilizing Carbonic-Acid Gas and similar gases; and I do hereby declare that the following is a full and exact description thereof, reference being had to the accompanying drawings, and to the letters of reference marked thereon.

The object of my invention is to collect, store, and utilize the carbonic-acid gas, and other gases which do not support combustion, generated in dwellings, stores, and other buildings, for the purpose of extinguishing fires that may occur, either by accident or through incendiarism, and, by means of suitable appliances, to keep a supply of such gas on hand, which can at any time be made available for this purpose, and which may be applied in such a manner as to greatly reduce the cost of the fire-department of a city, and at the same time avoid the immense loss in goods and merchandise which, under the present method of extinguishing fires, is necessarily occasioned by their being drenched with water.

The nature of this invention consists in collecting, by means of any suitable apparatus, the carbonic-acid gas, and similar gases possessing the property of extinguishing fire, generated by natural causes, in dwellings, stores, and other buildings, and conducting it into a suitable receiver or reservoir, by means of pipes attached to the furnace, stove, or range, or with the chimney of the building, this supply of gas being for the purpose of extinguishing fires which may occur either by accident or by incendiarism.

It also consists in providing a number of other receivers or reservoirs, of any suitable size and form, into which the gas is forced, by suitable means, from the receiver already mentioned. These are made very strong, so as to be capable of bearing a pressure of one hundred pounds or more to the square inch, and are connected together by suitable pipes, provided with stop-cocks, or other device for regulating the flow of gas from and to each other.

In these last-mentioned receivers, the gas is placed under pressure, so that it may be forced through suitable pipes to the place where it is required for extinguishing a fire; and when the supply of gas, generated as above described, is found insufficient, the gas may be generated artificially for these receivers, by means of the proper ingredients for producing such gas.

These receivers are of such number and capacity as may be requisite to supply a block, a number of blocks, or a whole city.

The figure represents a side elevation of one form

of apparatus employed for carrying out the object and design of my invention.

A may represent a furnace, stove, or similar apparatus, in which the gas is generated by combustion, and from which it is conducted, by the pipe B, constructed of suitable size and proper materials, into the receiver C, where it is collected.

This receiver may be made of any suitable material, and is provided with an aperture, a, at or near the top, for the purpose of allowing the lighter gases and atmospheric air to escape as the receiver becomes filled with the heavy gas.

Into this aperture a pipe may be inserted, if desired, for the purpose of carrying away the air and lighter gases; or one end of the pipe B may be inserted into the chimney of the building, for the purpose of drawing therefrom the carbonic-acid gas and similar gases into the receiver C, as shown by the dotted lines.

From this receiver C, the gas is forced into other receivers, D, through pipes and by suitable means.

The receivers D are made of any suitable form, very strong, and of such number and capacity as may be required to hold a sufficient quantity of gas for extinguishing any fire that may occur in the block or blocks of buildings which they are intended to supply.

The gas in these receivers is under pressure, so that it may be forced to any required point or locality, by means of pipes F F inserted therein, and passing through the walls into the various rooms or apartments of the buildings.

It will be seen, that by this means, a series of such receivers, connected together by pipes, may be constructed so as to supply a whole city.

When the supply of gas thus collected is found insufficient, the gas may be generated for the receivers D artificially, by chemical compounds, or suitable ingredients, such as marble-dust and sulphuric acid.

The advantages of my invention are evident, for the reason that this gas, introduced into a room or store, will extinguish any fire therein, without damaging the goods contained in it, and that this series of receivers may be managed and superintended, and the gas generated, either naturally or artificially, and stored, at little expense, thus very greatly diminishing the cost of keeping up appliances for extinguishing fires, which, under the present method of employing water for that purpose, are very expensive, and occasion much damage to goods by drenching them with water.

I may here state that I do not confine myself to nor claim any particular form of apparatus for collecting, generating, storing, and distributing the gas;

nor do I confine myself to the use of carbonic-acid gas only, as other gases possessing similar properties may be employed so as to produce the same results; but

What I claim as new, and desire to secure by Letters Patent of the United States, is—

The process, substantially as herein described, of extinguishing fires, the same consisting in storing the

carbonic-acid gas, or other equivalent gas, in one or more reservoirs, under pressure, and connecting said reservoirs with suitable pipes, as described.

ELI THAYER.
